E. HUGETZ.

SELF FILLING FOUNTAIN PEN.
APPLICATION FILED DEC. 17, 1920.

1,392,569.

Patented Oct. 4, 1921.

UNITED STATES PATENT OFFICE.

EDWARD HUGETZ, OF NEW YORK, N. Y.

SELF-FILLING FOUNTAIN-PEN.

1,392,569.

Specification of Letters Patent.

Patented Oct. 4, 1921.

Application filed December 17, 1920. Serial No. 431,415.

To all whom it may concern:

Be it known that I, EDWARD HUGETZ, a citizen of the United States of America, residing at New York city, county and State 5 of New York, have invented certain new and useful Improvements in Self-Filling Fountain-Pens, of which the following is a full, clear, and exact description.

This invention relates to improvements in 10 self-filling fountain pens, and has for one of its objects to provide a collapsible self-filling fountain pen; in other words, I have produced a pen made up of a plurality of collapsible or telescoping sections whereby 15 the pen, when not in use and collapsed can be carried in a vest pocket, in a lady's handbag or as a watch-charm. The barrel of the pen is provided with means to cause same to fill when properly manipulated, one of the 20 pen sections being arranged to assist in the actuation of the filling means, which in this instance is a piston.

I will now proceed to describe my invention in detail, the novel features of which I 25 will finally hereinafter claim, reference being had to the accompanying drawing, wherein:

Figure 1 illustrates a longitudinal sectional view of my improved pen in collapsed 30 condition;

Fig. 2 illustrates in elevation the sleeve to operate the filling piston, the sleeve being mounted on the pen-barrel which carries the pen-section, the pen section being also illustrated;

Fig. 3 is a fragmentary view illustrating the piston operating sleeve as pulled out either for preparing same to operate the piston or for writing purposes;

Fig. 4 is a similar view, illustrating the piston and operating sleeve therefor, as they would be positioned after a filling operation;

Fig. 5 is a sectional view, taken on a line 45 5-5 in Fig. 4;

Fig. 6 is a fragmentary view, enlarged, illustrating the various sleeves and manner of connecting same, said view being partly in section;

Fig. 7 is a fragmentary sectional view 50 illustrating the outer sleeve and its casing, also the cap to close the end of the outer sleeve; and

Fig. 8 illustrates in elevation the barrel- 55 sections extended for writing purposes.

As has been stated, one of the objects of

my invention is to provide a collapsible fountain pen that can be reduced into small space when not in use (see Fig. 1) and extended (see Fig. 8) for writing purposes. 60 Together with the above features I provide means whereby the pen can be filled by means of one of the slidable sections co-operating with a piston (in this instance) within the barrel of the pen. My improved 65 self-filling collapsible fountain pen is made up of a barrel-member 9 carrying the usual pen section 10 and a plurality of slidable sections 11 and 12. Each section 11 and 12 is made up of a sleeve and cover. The section 70 11 is made up of a sleeve 13 and cover 14 and the section 12 of a sleeve 15 and cover 16. Each sleeve 13 and 15 is provided with a slot, the slot in sleeve 13 being indicated by 17, and the slot in sleeve 15 by 18. These 75 slots will be covered by the covers or casings for the sleeves 13 and 15. The sleeves 13 and 14 are held together by a pin 19 (see Fig. 6), which extends beyond the cover 14 sufficiently to engage the slot 18 in sleeve 15 of 80 section 12. The cover 16 can be secured to sleeve 15 in any desired manner. The sleeve 15 extends at one end beyond the cover 16 to be engaged by a cap 20 to finish off the end of the pen. The slots 17 and 18 will, of 85 course, be long enough to permit of the desired movement upon the part of the sections 11 and 12.

By referring to Figs. 2, 3 and 4, it will be seen that sleeve 13 is provided with a branch 90 slot 21 communicating with one end of slot 17. The purpose of slot 21 is to engage a pin 22 carried by a piston 23 slidably mounted within the barrel 9. The pin 22 operates longitudinally of a slot 24 in the barrel 9. 95 The slot 24 will be closed by piston 23 when the piston is moved to the adjacent end of the barrel 9 to fill the barrel with ink. (See Fig. 5.) The movable sections 11 and 12 will have two slidable positions. In one 100 position the said sections can be extended or collapsed without operating piston 23. In the other position of said sections the piston may be operated.

Fig. 2 illustrates the normal position of 105 sleeve 13, in which position said sleeve can be moved longitudinally of the barrel 9 without operating the piston, this being obvious. To operate piston 23, it is but necessary to cause cross slot 21 to engage pin 22 by rotating the sections, after which the piston can be moved longitudinally of the barrel when 110

the sections are moved longitudinally of the barrel. Should piston 23 be located at the pen section end of the barrel, as indicated in Fig. 1, and the sections collapsed, it will merely be necessary to withdraw the sections until cross slot 21 alines with pin 21 (see Fig. 3), and then rotate the sections as per arrow in Fig. 3, which will cause slot 17 to move to the dotted line position, after which 10 pin 22 and cross slot 21 will be in engagement one with the other. The sections will now be moved still farther longitudinally of the barrel of the pen until the limit of such movement has been reached. Such movement will move piston 23 to the butt end of the barrel (see Fig. 5), thereby causing space 25 to fill with ink, the pen section 10 being of course introduced into a supply of ink. After the pen barrel becomes empty, the 15 piston 23 will be moved to the pen section end of the pen and then moved back to the butt end of the barrel. During the time that piston 23 is positioned at the butt end of barrel 9, the sections can be collapsed or extended without moving piston 23, for the reason that after the barrel is filled, the sections 11 and 12 will be rotatably moved to normal position to move cross-slot 21 out of engagement with pin 22.

20 The barrel 9 may be provided with index marks 26 and 27 to indicate when cross slot 21 is in alinement with pin 22 in either one of the two positions of the piston 23.

What I claim and desire to secure by Letters Patent is:—

1. In a collapsible self-filling fountain pen, a barrel having a slot therein, a piston within the barrel movable longitudinally thereof, a pin carried by the piston operable in said slot and extending beyond the peripheral surface thereof, a section carried by the barrel and movable longitudinally thereof, said section having a slot longitudinally thereof to receive said pin, and means associated with said slot to engage said pin whereby said piston can be operated by the movement of said section, said engaging means being normally out of engagement with said pin.
2. In a collapsible self-filling fountain pen, a barrel having a slot therein, a piston within the barrel movable longitudinally thereof, a pin carried by the piston operable in said slot and extending beyond the peripheral surface thereof, and a section carried by the

barrel and movable longitudinally thereof, having a slot longitudinally thereof, said section being also arranged for rotary movement, said slot at one end thereof having in communication therewith a cross slot to engage the pin carried by the piston, when said section has imparted thereto a rotary movement after said pin and cross slot are alined, whereby said piston can be operated by the longitudinal movement of the section, said cross slot and pin being normally out of engagement one with the other.

3. In a collapsible self-filling fountain pen, a barrel having a slot therein, a piston within the barrel movable longitudinally thereof, a pin carried by the piston operable in said slot and extending beyond the peripheral surface thereof, a section carried by the barrel and movable longitudinally thereof, having a slot longitudinally thereof, said section being also arranged for rotary movement, said slot at one end thereof having in communication therewith a cross-slot to engage the pin carried by the piston, when said section has imparted thereto a rotary movement after said pin and cross slot are alined, whereby said piston can be operated by the longitudinal movement of the section, said cross slot and pin being normally out of engagement one with the other, and means associated with the barrel to indicate when said pin and cross slot are in alinement.

4. In a self-filling fountain pen, a barrel, a piston within the barrel and movable longitudinally thereof, actuating means therefor, a section slidably mounted upon the barrel arranged to occupy thereon a filling position and a non-filling position, and means associated with the section to engage the actuating means for the piston when said section is in the filling position, whereby said piston will be operated when said section is moved longitudinally of the barrel, said section being out of engagement with the piston when in its non-filling position and capable of being moved longitudinally of the barrel without operating said piston.

Signed at New York city, N. Y., this 16 day of December, 1920.

EDWARD HUGETZ.
